THOMAS H. FERGUSON, OF OAKLAND, CALIFORNIA

OIL AND DRAFT REGULATING DEVICE

1,195,666.

Specification of Letters Patent. Patented Aug. 22, 1916.

Application filed September 15, 1915. Serial No. 50,869.

To all whom it may concern:

Be it known that I, THOMAS H. FERGUSON, a citizen of the United States, residing at Oakland, in the county of Alameda and State of California, have invented new and useful Improvements in Oil and Draft Regulating Devices, of which the following is a specification.

This invention relates to an oil and draft regulating device, particularly adapted for application to boilers and furnaces.

My invention is particularly adapted for use in connection with furnaces heated by liquid fuel, in which the fuel is vaporized and fed by steam generated by a boiler.

The object of the invention is to provide an improved and simplified mechanism for automatically regulating the draft of a furnace, the flow of oil through the burner, and the supply of steam in accordance with the variations in pressure of the steam in the boiler of the furnace.

Further objects will hereafter appear.

The invention consists of the parts and the construction and combination of parts as will hereinafter be more fully described and claimed, having reference to the accompanying drawings, in which—

Figure 1 is a central vertical section through the oil burner. Fig. 2 is a front view of the boiler and furnace showing the application of the invention. Fig. 3 is a detailed view of the damper control. Fig. 4 is another detailed view of the damper control. Referring in detail to the form of my invention illustrated herewith, it will be seen that I have illustrated a furnace A, having a boiler B, beneath which is a fire-box provided with the usual form of grate bars. Interposed between the grate bars and the doors or front portion of the fire-box is a plurality of horizontally disposed dampers such as indicated at 2, 3, 4, 5 and 6 which are pivotally mounted, as at 7, in collars 8, formed on the inner ends of shafts 9, which are journaled in bushings 10 secured in the front plate 11 of the furnace box. Secured on the outer end of each shaft 9 is a sprocket gear 12, said gears being positioned in alignment with each other, and turned by means of a sprocket chain 13, which is operated as will hereinafter be more fully described.

The main portion of the burner proper is positioned exterior of front plate 11 of the furnace box, being suitably secured thereto, while a burner tip proper projects through

the plate and interior of the furnace box, where it will assume a position directly above and in alignment with the damper indicated at 4. The oil burner proper consists of a casing 14, interior of which is formed the steam receiving chamber 15. Mounted in said chamber and adapted to be actuated by the steam pressure in the chamber is a diaphragm plate 16, which is secured to the casing by a rear plate or cap 17, which in turn is secured to the casing 14 by means of bolts 18. The cap 17 is hollowed out to form a chamber 19 on the rear side of the diaphragm plate 16. Screwed into the front portion of casing 14, or otherwise secured, is a bushing 20, interiorly of which is formed a valve seat 21, and formed exteriorly of the bushing and interiorly of an extension 22 formed on casing 14, is an annular chamber 23 to which oil is admitted from a suitable source of supply, as a pump or similar means not here shown, by means of a pipe 24.

Mounted interiorly of the bushing 20 and adapted to form a closure for the seat 21 is a cone shaped valve 25, one end of which is provided with an extension 26 which passes through and is secured to the diaphragm plate 16 by means of a collar 27 and a nut 28. The valve 25 is provided with a central passage 29, the outer end of which is threaded to receive a tubular extension 30 on the outer end of which is secured a cone shaped valve 31, which is adapted to form a closure 32 for the seat 32 formed in the burner tip 33; the valve 31 being provided with a central passage 34 which communicates with the tubular extension or pipe 30 and the central passage 29 formed in valve 25. The steam is admitted to the central passage 29 from chamber 15 through a plurality of radially disposed ports 35 formed in the extension 26, and oil is admitted to the central passage 29 from the annular chamber 23 through an angularly disposed port 36 formed in valve 25, which communicates with an annular recess 37 formed in the face of the valve, and the annular recess in turn receives oil from a plurality of radially disposed ports 38 which communicate with the annular chamber 23.

The operation of the burner proper will be as follows: With the steam admitted to chamber 15 direct from the boiler, through a pipe 39, the pressure will under normal conditions not be sufficient to operate the

diaphragm to cause same to move valve 25 into engagement with its seat 21. In other words, under normal conditions valve 25 will assume an open position and permit 5 the steam to escape between the valve and the valve seat into the burner tip. With the valve open it will also be seen that oil is permitted to escape through the several ports 38. The passage of steam and oil by 10 the valve at this point causes a thorough atomization, and the combustible mixture thus produced escapes through the discharge orifice 40 of the burner tip directly into the furnace, where combustion takes place. The 15 moment the steam pressure in the boiler reaches a predetermined fixed point the pressure in chamber 15 will become sufficient to actuate diaphragm plate 16, and cause this to close valve 25 against its seat 21, in this 20 manner either entirely closing off the supply of oil and steam that passes between the valve and seat or reducing the space between the valve and seat to such an extent that the volume of oil and steam passing 25 by is so reduced that the fire in the furnace box will be proportionately reduced, in this manner permitting an automatic regulation of the fire. A drop in steam pressure will permit the diaphragm to proportionately 30 open the valve, and correspondingly or proportionately increase the fire. From the foregoing it will be seen that an increase in pressure beyond a pre-determined point reduces the fire, while a decrease in pressure 35 increases the fire.

In the operation of a burner of the character described it is found advantageous to automatically regulate the draft or admission of air, so that this will be proportionate 40 to the fire. This is accomplished in the present instance by the following means: Mounted in a suitable position on the front plate 11 of the fire-box is a diaphragm valve 45^a, one side of which is connected by a pipe 46 with the chamber 19 formed in cap 17. The 45 opposite side of the diaphragm valve 45 is connected with a rod 47, which in turn is connected with a lever 48 pivotally mounted, as at 49, on a bracket 50. The outer end of 50 this rod is attached to the sprocket chain 13, while the opposite end of the sprocket chain is connected with a movable weight 51. Mounted on the pipe line 46 is a valve 52 of suitable construction. A pump is attached 55 to this valve and air is forced through pipe 46 to fill chamber 19 and chamber 53 with air, the pressure of which is determined by the desired boiler pressure. For instance, if it is decided to normally maintain 180 60 pounds of pressure in the boiler it is necessary to pump sufficient air through valve 52 to produce 180 pound pressure in chambers 19 and 53. It can therefore be seen that the diaphragm plate 16 which is subjected to 180 65 pound pressure on its rear side will always

hold the valve 25 in an open position until the boiler pressure reaches 180 pounds or a little in excess thereof. The steam pressure in chamber 15, when the excessive boiler pressure has been reached, will then overcome the pressure in chamber 19, and consequently cause the diaphragm plate to move the valve 25 into closed or partially closed position. Any movement of the diaphragm plate 16 by the fluctuation of the boiler pressure or pressure in chamber 15 causes, as 70 previously described, an increase or decrease of fire in the furnace box. It also causes a fluctuation of pressure in chambers 19 and 53, which are connected by pipe 46, and 75 therefore causes a movement of diaphragm 45. This movement is transmitted through link 47 and lever 48, causing this to swing on pivot 50, and as the sprocket chain 13 is connected to the lever it will be seen that 80 this will move back and forth over the sprocket wheels 12, causing these, with connected shafts 9, to revolve in bushings 10, thereby opening and closing the several damper plates, closing same when the fire is 85 reduced and proportionately opening same when the fire increases. This movement of the damper plates is transmitted through shafts 9 by means of lugs 60 formed on the end of collars 8. These lugs are positioned 90 at different points on the several collars. For instance, a slight movement of the chain in the direction of arrow *a*, see Fig. 3, will cause the lug 60 to engage damper plate 4 and move this into a tilted position. A further movement of the chain will cause similar lugs to engage the damper plates 3 and 5 and lift these in unison; while a further movement of the chain will cause the lugs adjacent to damper plates 2 and 6 to engage 105 and lift same. From this description it will be seen that with a small fire it is possible that the damper plate 4 is only slightly opened. As the fire increases this damper plate 4 will be further opened and damper 110 plates 3 and 5 will probably be slightly opened: the open position of all damper plates being assumed when the largest possible fire is obtained. The damper plates are automatically closed as they are pivoted 115 sufficiently off center to normally move to closed position, and are only open when engaged by the adjacent lugs, it being understood that each collar 8 is provided with a lug, and that these lugs are placed in different positions on the various collars as 120 previously described.

The central passage 29 and pipe 30, together with the connected ports 35 and 36, are only provided for the purpose of admitting a small quantity of steam and oil to the furnace when valve 25 has been moved to closed position by excessive pressure in the boiler. Valve 31 will also assume a closed position when valve 25 closes. The steam 130

from chamber 15 is thus permitted to enter through the radial ports 35 and oil through port 36 and the mixture of steam and oil thus produced is discharged through the central opening in valve 34 and the orifice 40. A small fire is in this manner maintained at all times.

For the purpose of protecting the diaphragm plate 16 against injury means have been provided for limiting the movement of same. This is accomplished by providing a set screw 65 which enters chamber 19. The inner end of this set screw is provided with an annular recess 66 into which project a pair of set screws or pins 67, carried by the nut 28. The movement of the diaphragm is in this way positively limited by the length of the recess 66. For instance, from the previous description it will be remembered that chamber 19 contained air under pressure which approximated 180 pounds, and this pressure is always maintained, whether the boiler is in operation or not. It can, therefore, be seen that if the boiler was cold, and that the steam pressure was reduced considerably, or in some instances entirely absent no pressure would be maintained in chamber 15. The excessive pressure in chamber 19 would then exert its full force on the diaphragm plate 16 and rupture same, as it would not be counter-balanced by any pressure in chamber 15. This is, however, prevented in the present instance as the pins 67, will engage shoulder 66^a and only permit the diaphragm to move a certain distance. Any injury to the diaphragm is in this manner overcome.

For the purpose of preventing any leakage of steam by valve 25 which might back into the oil line through ports 38 and the annular chamber 23, an annular groove 68 has been formed in the face of the valve. Any steam having a tendency to leak will in this instance collect in the annular groove 68, and is permitted to escape therefrom by a port 69 into the burner tip, thereby preventing admission of steam to the oil line.

The valve indicated at 31 is provided for two purposes: First, to further break up or atomize the steam and oil which was primarily mixed when passing by valve 25, and second, to prevent reduction of pressure in the burner tip as much as possible when a small fire is burning,—this being of considerable importance, as too much reduction of pressure in the burner tip has a tendency to permit the oil and steam to condense and settle in the tip before it discharges.

The device here shown is simple and substantial in construction and may be applied to any form of boiler and furnace-box now in use.

The device may be set to suit any pressure desired, the pressure desired being controlled or regulated by the air pressure in

chambers 19 and 53, and this pressure is automatically maintained as the fire in the furnace-box and the air admitted thereto is automatically maintained by the diaphragm valves.

Having thus described my invention, what I claim and desire to secure by Letters Patent is—

1. The combination with a boiler, a furnace and a plurality of dampers mounted in the furnace of a liquid fuel burner, said burner comprising a casing, having a chamber formed therein, a diaphragm valve dividing said chamber into two compartments, a second diaphragm valve, a pipe connecting one side of said diaphragm valve with one side of the first named diaphragm valve, means for charging said pipe with a fluid under pressure, means for admitting steam direct from the boiler to the casing chamber on the other side of the first named diaphragm valve to normally counteract the fluid pressure, a burner tip on the casing, a valve mounted in said tip between the chambers in the casing, and the tip, a connection between the first named diaphragm and the valve to open or close the valve, means for admitting oil to the burner, at a point where its flow, together with steam from the casing chamber, will be controlled by the valve, and means controlled by the second diaphragm valve to open and close the dampers on the furnace in unison with the valve substantially as described.

2. The combination with a boiler, of a liquid fuel burner, said burner comprising a casing having a steam chamber formed therein supplied with steam directly from the boiler, a burner tip connected with one end of the steam chamber and forming an outlet therefor, a diaphragm valve in the chamber adapted to be actuated by the steam pressure in the chamber, a valve interposed between the burner tip and the chamber directly connected with the diaphragm valve and adapted to open or close communication between the chamber and burner tip, and an oil delivering pipe connected with oil ducts formed in the casing which are adapted to be opened and closed by the valve.

3. The combination with a boiler, of a liquid fuel burner, said burner comprising a casing having a steam chamber formed therein supplied with steam directly from the boiler, a burner tip connected with one end of the steam chamber and forming an outlet therefor, a diaphragm valve in the chamber adapted to be actuated by the steam pressure in the chamber, a valve interposed between the burner tip and the chamber directly connected with the diaphragm valve and adapted to open or close communication between the chamber and burner tip, an oil delivering pipe connected

- with oil ducts formed in the casing which are adapted to be opened and closed by the valve, and means for maintaining a pilot fire when the valve is closed, said means 5 comprising a pair of ducts formed in the valve, one of said ducts forming communication between the steam chamber and the burner tip, and the other duct forming communication between one of the oil ducts and 10 the burner tip.
4. The combination with a boiler, a furnace and a plurality of dampers mounted in the furnace, of a liquid fuel burner, said burner comprising a casing having a chamber formed 15 therein, a diaphragm valve dividing said chamber into two compartments, a second diaphragm valve, a connection between said diaphragm valves, means for charging said connection with a fluid under pressure, 20 means connected with the second diaphragm valve for maintaining said pressure constant, means for admitting steam directly from the boiler to the burner casing chamber on the other side of the first named dia- 25 phragm valve to counteract the fluid pressure between the diaphragm valves, a burner tip connected with one end of the steam chamber and forming an outlet therefrom, a valve interposed between the burner 30 tip and the chamber directly connected with the diaphragm valve and adapted to open or close communication between the chamber and burner tip, means for admitting oil to the casing at a point where its flow, to- 35 gether with the steam from the chamber, will be controlled by the valve, and means controlled by the second diaphragm valve for opening and closing the dampers on the furnace in unison with the valve.
- 40 5. The combination with a boiler, of a liquid fuel burner, said burner comprising a casing having a steam chamber formed therein, a diaphragm valve dividing said chamber into two compartments, a second 45 diaphragm valve, a pipe forming communication between one side of said diaphragm valve and the first diaphragm valve, means for charging said pipe with a fluid under pressure, means for maintaining said pres- 50 sure constant, means for admitting steam directly from the boiler to the burner casing chamber on the other side of the first named diaphragm valve to counteract the fluid pressure between the diaphragm 55 valves, a valve in the burner casing directly connected with the first named diaphragm valve separately controlling the escape of the steam admitted and oil from another source of supply before they are permitted 60 to combine, and means for limiting the movement of the first named diaphragm valve.
6. The combination with a boiler, of a liquid fuel burner, said burner comprising 65 a casing having a steam chamber formed
- therein, a diaphragm valve dividing said chamber into two compartments, a second diaphragm valve, a pipe forming communication between one side of said diaphragm valve and the first diaphragm valve, means for charging said pipe with a fluid under pressure, means for maintaining said pressure constant, means for admitting steam directly from the boiler to the burner casing chamber on the other side of the first named diaphragm valve to counteract the fluid pressure between the diaphragm valves, a valve in the burner casing directly connected with the first named diaphragm valve controlling the escape of the steam admitted and oil from another source of supply, an adjusting screw passing through the fluid pressure side of the burner casing chamber having an annular groove formed in its end, a plate secured on the fluid pressure side of the first named diaphragm valve, and members on the plate projecting into the groove to limit the movement of the diaphragm valve.
7. An oil burner comprising a casing having a chamber formed therein adapted to be directly connected to a boiler, a second chamber in the casing connected with a source of oil supply, a burner tip, a valve seat and opening formed in the casing between the burner tip and the steam chamber, said casing also having ports formed therein which connect with the oil chamber and open through the valve seat, a valve on the seat adapted to close off or regulate the escape of oil through the ports and simultaneously close off or regulate the volume of steam escaping from the steam chamber, and means for opening or closing the valve.
8. An oil burner comprising a casing having a chamber formed therein adapted to be directly connected to a boiler, a second chamber in the casing connected with a source of oil supply, a burner tip, a valve seat and opening formed in the casing between the burner tip and the steam chamber, said casing also having ports formed therein which connect with the oil chamber and open through the valve seat, a valve on the seat adapted to close off or regulate the escape of oil through the ports and simultaneously close off or regulate the volume of steam escaping from the steam chamber, and means automatically controlled by the steam pressure in the boiler to open or close the valve.
9. An oil burner comprising a casing having a chamber formed therein adapted to be directly connected to a boiler, a second chamber in the casing connected with a source of oil supply, a burner tip, a valve seat and opening formed in the casing between the burner tip and the steam chamber, said casing also having ports formed therein which connect with the oil chamber and

open through the valve seat, a valve on the seat adapted to close off or regulate the escape of oil through the ports and simultaneously close off or regulate the volume of steam escaping from the steam chamber, and a diaphragm valve in the steam chamber directly connected with the first-named valve to automatically open or close same.

In testimony whereof I have hereunto set my hand in the presence of two subscribing **10** witnesses.
